Primary Examiner — John A Voytek(74) *Attorney, Agent, or Firm* — ScienBiziP, P.C.(57) **CLAIM**

The ornamental design for a hot air balloon, as shown and described.

DESCRIPTION

FIG. 1 is a front, right and top perspective view of a hot air balloon, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of an area labeled 9 in FIG. 2 comprising a hanging hole.

The dot-dash boundary lines in FIGS. 2 and 9 demarcate a portion of the article annotated for enlargement purposes.

1 Claim, 9 Drawing Sheets
